CLAIM

The ornamental design for a container mounting apparatus, as shown and described.

DESCRIPTION

FIG. 1 is a top, front, right perspective view of a container mounting apparatus showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front, right perspective view of another example container mounting apparatus of our design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The uneven-length broken lines represent unclaimed boundaries of the claimed design. The broken lines showing the remainder of the container mounting apparatus are for environmental purposes only and form no part of the claimed design. The bracketed portions shown in FIGS. 8-12 showing a break in the surface represent indeterminate length and form no part of the claimed design.
